UNITED STATES PATENT OFFICE.

AXEL ANDERSON, OF ST. PAUL, AND CARL O. WOLD, OF MINNEAPOLIS, MINNESOTA,
ASSIGNORS TO RUSSELL GRADER MANUFACTURING CO., OF MINNEAPOLIS, MINNE-
SOTA, A CORPORATION.

GRADER BLADE.

1,406,325.

Specification of Letters Patent. Patented Feb. 14, 1922.

Application filed November 14, 1917. Serial No. 201,956.

To all whom it may concern:

Be it known that we, AXEL ANDERSON and CARL O. WOLD, citizens of the United States, residents of St. Paul, county of Ramsey, State of Minnesota, and Minneapolis, county of Hennepin, State of Minnesota, respectively, have invented certain new and useful Improvements in Grader Blades, of which the following is a specification.

10 The object of our invention is to provide a grader blade composed of a plurality of sections mounted for adjustment on a horizontal or a vertical axis for the purpose of moving the blade sections forward or backward or up or down, as the grading work may require.

Other objects of the invention will appear from the following detailed description.

20 In the accompanying drawings forming part of this specification,

Figure 1 is a rear view of a portion of a grader blade, composed of abutting sections, showing the means for adjusting them upon a vertical and a horizontal axis.

Figure 2 is a plan view of the same.

Figure 3 is a vertical sectional view through a section of the blade and the adjusting means therefor,

30 Figure 4 is a plan sectional view of a portion of adjacent blade sections, showing the lapping ends of the sections and the vertical axis therefor.

Figure 5 is a detail sectional view of the vertical pivot on which the sections swing forwardly or backwardly.

Figure 6 is a detail sectional view of a modified construction.

In the drawing, 2 and 3 represent adjoining sections of the grader blade which may be composed of two sections jointed in the manner shown, or may include several of such sections depending upon the size of the machine and the character of the work where it is to be used. We have only shown one joint which will be sufficient to illustrate the principle involved and reserve the right to use as many of these joints as may be desired.

50 In the preferred construction the adjoining ends of the blade sections lap by each other, as shown in Figure 4, and each section is provided with a channel bar 4 in the rear thereof, centrally secured to the

section of the blade by suitable means, such as bolts 5. To the top of these channel bars brackets 6 are secured, having threaded studs 8 and 9 which have a swivel joint 10 between them and are revolved in said brackets by means of a suitable handle 11 which is free to slide in the coupling between the studs. When this handle is moved, the studs will be fed forward or backward to separate the brackets 6 or draw them together. The studs are located as stated at the top of the scraper blade and evidently when the brackets are moved apart by the revolution of the studs the adjacent ends of the scraper sections will be tilted to raise the inner ends of the sections and depress the outer ends thereof and thereby adapt the blades for making a more pronounced slant or inclination in the grade of the road. When the handle 11 is revolved to draw the brackets together, the inner ends of the sections will be depressed and the outer ends elevated and the longitudinal edges of the sections may, if desired, be brought into alignment so that the blade will be substantially straight from end to end. This adjustment will cause the scraper to form a substantially flat surface in the soil over which it is moving.

It is also desirable in a blade of this type to shift the sections forward or backward on a vertical axis and to accomplish this we provide angle iron brackets 12 on the lower flanged portion of the channel bars upon which we mount blocks 13 having threaded sockets for studs 14 and 15 provided with a swivel joint between them corresponding to the one described, and also having an operating handle 11^a which, when moved back and forth, will impart a corresponding movement to the threaded studs. We also provide plates 16 horizontally arranged and secured to the underside of the channel bars and having a vertical pivot 17 which passes through the lapping edges of the plate 16 and through the lower flanges of the channel bars 4, so that when the studs 14 and 15 are revolved, the blade sections will be moved forward or backward on a vertical axis for adjustment to the desired angular relation. A rocker washer 18 is preferably provided on said vertical axis between the plates 16 to provide sufficient freedom of movement of the plates, one upon the other, to allow for adjustment of the

- blade sections on a horizontal axis without binding or cramping. This rocker washer, however, is not a necessity, as we have found there is sufficient spring or flexibility in the 5 plates 16 themselves to permit the desired vertical adjustment of the blade sections without the necessity of having any more than an ordinary pivotal connection for the vertical axis of the blade sections.
- 10 It will be noted that the studs for moving the blade sections on a vertical axis are in the rear of the others so that independent adjustment is permitted and one set of adjusting studs will not in any way interfere 15 with the other set.

In Figure 6 we have shown a slightly modified construction in which the grader blade sections are placed end to end in abutting relation and a plate 19 is secured to one 20 section in position to lap by the corresponding end of the other section, the adjustment of the sections one upon the other being effected in substantially the same manner as described with reference to the previous 25 figures.

In various ways the details of construction herein shown and described may be modified and still be within the scope of our invention.

30 We claim as our invention:

1. A grader blade composed of a plurality of sections placed end to end and means having threaded connections with said sections for adjusting them on a horizontal 35 transverse axis to relatively raise or lower the abutting ends of said sections.

2. A grader blade composed of a plurality of sections placed end to end, adjusting studs mounted in said sections respectively 40 in the rear of the abutting ends of said sections, the opposite studs having a swivel connection between them and means for revolving said studs to raise or lower the adjacent ends of said sections on a horizontal 45 transverse axis.

3. A grader blade composed of a plurality of sections placed end to end, adjusting means carried by said sections respectively in the rear of the abutting ends thereof and 50 extending lengthwise of said sections for adjusting the sections on a horizontal transverse axis to raise or lower the abutting ends of said sections.

4. A grader blade comprising sections 55 placed end to end, a pair of adjusting studs supported by said sections in the rear of their abutting ends and near the upper edges thereof for adjustment of said sections on a horizontal axis, and similar adjusting 60 studs supported in the rear of said first named studs and near the bottom of said

sections for adjustment thereof on a vertical axis.

5. A grader blade composed of a plurality of sections placed end to end, said sections 65 having a vertical pivotal connection between their abutting ends, said pivotal connection allowing relative movement of said sections on a vertical and a horizontal axis, and means supported by said sections adjacent said 70 pivotal connection for adjusting said sections vertically or horizontally.

6. A grader blade comprising sections placed end to end, brackets projecting from the abutting ends of said sections, studs having swiveled connections between them bridging said abutting ends and having threaded connections with said brackets for tilting said sections vertically or horizontally, and guide plates for the lower 80 portions of the abutting ends of said sections.

7. A grader blade composed of a plurality of sections placed end to end, studs having their abutting ends swiveled together and bridging said abutting ends, and extending 85 lengthwise of said sections, means connecting said studs with said sections respectively for adjusting them on a horizontal and vertical axis.

8. A grader blade comprising sections 90 having their ends in abutting relation, brackets mounted on said abutting ends, studs having a swiveled connection between them and mounted in said brackets for longitudinal adjustment, movement of said 95 studs lengthwise in said brackets operating to shift said sections on a horizontal or vertical axis, for the purpose specified.

9. A grader blade composed of sections placed end to end, brackets carried by said 100 sections near their abutting ends, studs having threaded connections with said brackets and a swivel connection between them, revolution of said studs tilting said sections vertically to change the angle of the lower edges 105 of said sections to the ground line.

10. A grader blade comprising sections placed end to end, plates carried by said sections and bridging the abutting ends thereof, one plate having a pivotal bearing upon 110 the other plate and means in the rear of the pivotal bearing of said plates for shifting them on a vertical axis to change the angle of the abutting ends of said sections.

In witness whereof, we have hereunto set 115 our hands this 31st day of October, 1917.

AXEL ANDERSON.
CARL O. WOLD.
